UNITED STATES PATENT OFFICE.

MORRIS M. GRUBER, OF EAST ORANGE, NEW JERSEY, ASSIGNOR, BY MESNE ASSIGNMENTS, TO SONORA PHONOGRAPH COMPANY, INC., OF NEW YORK, N. Y., A CORPORATION OF NEW YORK.

TONE ARM FOR PHONOGRAHS.

Application filed July 12, 1923. Serial No. 650,992.

This invention relates to tone arms for phonographs. These arms usually comprise two parts, one part mounted in the motor-board of the machine for pivotal movement about a vertical axis, and the other part which carries the sound box pivotally connected to said first part for moving about a horizontal axis. In certain types of phonographs, it has been the practice to provide the first of said parts, that is, the part pivoted for movement about a vertical axis, with a cylindrical bearing at its end into which is fitted a similarly-shaped journal carrying the first of said parts. Said bearing and journal portions were of comparatively large diameters, that is, an inch or more, so that the cylindrical bearing surface was comparatively large. This resulted in difficulty in obtaining a close fit between these parts, for as is well known, it is much more difficult to fit a journal in a bearing of large diameter than in one of small diameter, and, in addition, the large-surface bearings wear much more rapidly. The result of these imperfect fittings was a rattling between the parts, which caused an imperfection in the nature of a chattering sound, in the playing of a record. It is one of the objects of my present invention to overcome the disadvantages hereinbefore specified and others, and to provide a novel swivel connection between the parts of the tone arm, whereby any possibility of chattering is eliminated.

It is a further object of my invention to provide in the swivel joint a bearing of a relatively small diameter, thus making it possible to obtain exact fittings between the journal and the shaft of said joint.

It is a further object of my invention to provide a construction similar to that previously used in the respect that a cylindrical portion of large diameter is formed on the end of the part of the tone arm which is vertically pivoted, and in said cylindrical portion is fitted a cooperating cylinder which carries the other part of the tone arm but without possibility of any defect in transmission of sound being caused by imperfection of fit between said cylindrical portions.

It is a further object of my invention to provide a swivel joint between the parts of the phonograph tone arm which will not be

rendered defective by wear of the parts, even after a long period of use.

Other objects and advantages will appear as the nature of the improvements is better understood, the invention consisting substantially in the novel arrangement and correlation of instrumentalities herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive, standpoint.

The inventive idea involved is capable of receiving a variety of mechanical expressions, one of which, for the purposes of illustration, is shown in the accompanying drawings, in which

Fig. 1 is a front view of a phonograph tone arm having my invention applied thereto.

Fig. 2 is a plan view of the tone arm shown in Fig. 1.

Fig. 3 is a disassembled view of the tone arm shown in Figs. 1 and 2, parts being broken away to illustrate the underlying structure.

Fig. 4 is a section taken on the line 4—4 of Fig. 2.

Fig. 5 is a vertical section taken substantially on the line 5—5 of Fig. 2.

Referring to the drawings, there is shown a phonograph horn which may be of any ordinary type but more particularly that employed in the machines of the concealed horn type, and consists of two parts 10 and 11, part 10 being rotatably mounted in a collar 12 which is secured to the motor-board 13 in any suitable manner, as by screws 14, and the part 11 being swiveled to the part 10 and adapted to carry at its forward end 16 the reproducer or sound box (not shown). The part 10 may be referred to in this specification as the "amplifying portion of the arm", while the part 11 may be referred to as the "reproducer part". The part 10 is, therefore, rotatable about a vertical axis,

which may be indicated at A—A, so that the tone arm may travel in a horizontal plane. The part 11 is swiveled to the part 10 for rotation about a horizontal axis, which may be indicated at B—B, so that the reproducer may be lowered into contact with the phonograph needle or raised out of contact therewith.

In order to pivotally connect the part 11 to the part 10 by a swivel joint, the part 10 is provided at its forward end with a cylindrical portion 15, the axis of which is horizontal. Within said cylindrical portion is adapted to fit a barrel 18. The cylinder 15 is provided with a cut-out portion 20 extending substantially half way around its circumference, in which space the portion 11 is adapted to operate. Said portion is provided with a cylindrical rearward end 21 adapted to fit into the barrel 18 by way of cut-out portion 23, which is of a size sufficient to accommodate cylindrical portion 21 snugly. The cut-out portion 23 is smaller than cut-out portion 20, so as to permit movement of arm 21 and barrel 18 to which it is connected about a horizontal axis within cylindrical portion 15. The barrel 18 is, of course, hollow, to permit the transmission of sound waves therethrough into the amplifying portion 10.

In previous constructions, the barrel 18 was ground to a snug fit within the cylindrical portion 15 which acted as a bearing. The portion 15 was usually an inch or more in diameter, and its length also in excess of one inch. In order to make an accurate bearing, careful machining was necessary and rendered the task a difficult one. Even if the bearing were correct when originally made, constant use would soon cause a certain amount of wear, and barrel 18 would have a certain amount of free play within bearing 15 and thus set up a rattling sound, which destroyed the effect of the record which was being played at the time. By my invention I eliminate the large-diameter, large-surface bearing 15, and provide a very small-diameter, small-surface bearing which is easily manufactured and which, even after long use, develops very little, if any, lost motion or free play. For this purpose I provide a shaft 25 supported in end members 26, 27, each of said end members having a shoulder 28, 29 respectively adapted to seat against the peripheries 30, 31 respectively at the ends of the cylindrical portion 15. Said shaft 25 may be in the form of a bolt extending through the end members 26, 27, said bolt being provided with a head 32 at one end and having a threaded portion 33 at its other end, on which is adapted to screw a nut 34, which enters a depression 35, formed in the end member 27, so that said nut is countersunk. By drawing up the bolt 65 tightly against the two end members 26 and

27, said end members are brought into firm engagement with the edges 30, 31 of the cylindrical portion 15, so that no movement can take place between said end members and said cylindrical portion. The shaft 25 is thus firmly and rigidly fixed in position relative to cylindrical portion 15 and amplifying portion 10 of the tone arm. Upon this rigid shaft 25, I rotatably mount the barrel 18. For this purpose I provide said barrel with inset heads 40, 41 at the center of which I form hubs 42, 43, the opening through said hubs being ground to a size just sufficient to permit the barrel 18 to be rotated freely on shaft 25 without appreciable free play or lost motion. It is thus apparent that the only contact of the barrel 18 with its supporting shaft is by the small-diameter, small-surface hubs 42, 43. The contacting surfaces between the hubs or bearings and the shaft journalled therein are so small that accuracy in fitting is easily obtained and the wear upon said contacting surfaces is negligible, even after a long period of use. It is therefore apparent that it is now no longer necessary to fit the barrel 18 accurately within cylindrical portion 15 because the movement of said barrel relative to cylindrical portion 15 is determined by the bearings 42, 43 and shaft 25, rather than by

the large-diameter, large-surface bearings between the circumference of portion 18 and the inner surface of cylindrical portion 15. So that, if there is an accurate fit of shaft 25 in the small bearings 42, 43, which is easily obtainable, there will be no rattling of the barrel 18 within cylindrical portion 15, even if there is a great deal of space between said barrel and said portion.

Within one of the depressions formed by the wall of the cylinder and the inset heads 40 and 41 (here shown as the depression formed by the head 41) is positioned a leaf spring 50 carrying at one end a detent 51, extending through the wall of the barrel 18, and adapted to contact with grooves 52 and 53 for maintaining the reproducer portion 11 in raised or lowered position.

In accordance with the provisions of the patent statutes, I have described the principle of my invention together with the apparatus which I now consider to represent a practical embodiment thereof, but I desire it understood that my invention is not confined to the particular form of apparatus herein shown and described, the same being merely illustrative, and that the invention can be carried out in other ways without departing from the spirit of my invention, and, therefore, I claim broadly the right to employ all equivalent instrumentalities coming within the scope of the appended claims, and by means of which the objects of my invention are attained, and the new results accomplished, as herein set

forth, as it is obvious that the particular embodiments herein shown and described are only some of many that can be employed to attain these objects and accomplish these 5 results.

Having described my invention, what I claim and desire to secure by Letters Patent is:

1. A device of the character described comprising a tone arm having a reproducing section and an amplifying section, a joint connecting said sections comprising a hollow cylinder carried by one of said sections and a second hollow cylinder carried by the other 10 of said sections and adapted to fit concentrically within said first cylinder, said second cylinder having inset heads each provided with a central hub, end plates for said first cylinder each provided with a central 15 perforation and a shaft adapted to pass through said hubs and said perforations and to form an axle to rotatably support the second cylinder in spaced relation to said first cylinder and a leaf spring positioned upon the inner wall of said second cylinder against one of said heads, said 20 spring having a detent projecting through the wall of said cylinder and adapted to engage grooves in the wall of said first cylinder whereby said reproducer portion of said tone arm 25 may be locked by said detent in raised or lowered position.

of said tone arm may be locked in raised or lowered position.

2. In a device of the character described a tone-arm having a reproducer section and an amplifying section, a joint connecting 35 said sections comprising a hollow cylinder carried by one of said sections, said cylinder having end plates adapted to form closures for said cylinder, a second cylinder carried by the other of said sections, said second cylinder being positioned within and concentric with the first cylinder and being provided with inset heads carrying hollow hubs, a shaft extending through said plates and rotatably mounted in said hubs, means 40 carried by said shaft and engaging said plates to hold said shaft against movement relative to said plates and a leaf spring positioned upon the wall of said second cylinder against one of said heads, said spring having 45 a detent projecting through the wall of said cylinder and adapted to engage grooves in the wall of said first cylinder whereby said reproducer portion of said tone arm 50 may be locked by said detent in raised or 55 lowered position.

This specification signed this 15th day of June, 1923.

MORRIS M. GRUBER.
